Primary Examiner — Eric Goodman*Assistant Examiner* — Amy Wierenga(74) *Attorney, Agent, or Firm* — Senniger Powers LLP(57) **CLAIM**

I claim the ornamental design for a gutter cover, as shown and described.

DESCRIPTION

FIG. 1 is a top front perspective view of a gutter cover of my design.

FIG. 2 is a left end view of the gutter cover, the right end view being a mirror image of FIG. 2.

FIG. 3 is a front view of the gutter cover.

FIG. 4 is a top view of the gutter cover.

FIG. 5 is a rear view of the gutter cover; and,

FIG. 6 is a bottom view of the gutter cover.

The dashed broken line showing is included for the purpose of illustrating portions of the article that form no part of the claim. The dash-dot-dash broken line showing depicts the boundaries of the claim and form no part thereof. FIGS. 1, 3, 4, 5 and 6 are shown with a symbolic break in the gutter cover's length. Any portion of the article between the break lines forms no part of the claim.
